(57) **CLAIM**

The ornamental design for an LED light, as shown and described.

DESCRIPTION

FIG. 1 is a front, top, left perspective view of the LED light; FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The claimed design is indicated by the relatively dark portions in the drawings, while the relatively light portions are form no part of the claimed design. Shading is used to illustrate the curvature of the LED light.
